(57) **CLAIM**

We claim the ornamental design for a drinking container, as shown and described.

DESCRIPTION

FIG. 1 is a perspective top view of a new design for a drinking container;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The horizontal broken line in FIG. 4 represents a seam line. The remainder of the broken lines in the drawings depict portions of the drinking container that form no part of the claimed design.
